UNITED STATES PATENT OFFICE.

HARRY M. KORETZKY, OF NEW YORK, N. Y.

PORTABLE ELECTRIC LIGHT.

1,392,420.

Specification of Letters Patent. Patented Oct. 4, 1921.

Application filed March 10, 1920. Serial No. 364,635.

To all whom it may concern:

Be it known that I, HARRY M. KORETZKY, a citizen of the United States, residing in New York city, State of New York, have invented a certain Improvement in Portable Electric Lights, of which the following is a specification.

The present invention relates to certain improvements in that class of portable electric lights in which the current is supplied to a lamp bulb carried at one end of a casing, from a battery within such casing; and the principal object of the invention is to provide a cheap and reliable mounting for the lamp and its usual reflector which may be readily applied either to a metal or non-metallic casing. The improvement is so constructed and arranged as to avoid connecting any external metal parts to opposite battery poles, thereby preventing all danger of running down the battery by accidental short-circuits. Another advantage of the invention is found in the fact that it makes the assembling of the entire apparatus very simple, and lessens the expense of labor and material involved in what may be called the internal wiring of the casing.

A minor feature of the improvement relates to a novel push-button arrangement whereby the lighting of the lamp is controlled at will.

Certain preferred forms of the invention are illustrated in the accompanying drawings, wherein Figure 1 is a view in longitudinal section of a metallic casing provided with the improvements in question, Fig. 2 is a similar view of a fiber (or other insulating) casing provided with the invention, Fig. 3 is an elevation of the push button and its cover plate, Fig. 4 is a longitudinal sectional view of the same, Fig. 5 is a sectional view of the same on the line 5-5 of Fig. 3, and Fig. 6 is a sectional view of a modified form of contact plate.

In Fig. 1, the battery 10, with its insulating covering 11, is shown within the metal casing 12, being confined by the screw cap 13, which is provided with the spring 14, whose function is to create a firm contact of the upper or carbon end of the battery with the central lamp terminal and, at the same time, to provide electrical connection between the zinc in the lowermost battery cell and the cap and casing. All of this is, of course, well known in the art.

In order to complete the circuit, when de-

sired, in a manner hereafter described, a contact plate is employed which is permanently in electrical connection with the external or screw-threaded terminal of the lamp bulb, and is placed between the side of the upper end of the insulated battery and the interior of the casing, but without touching this latter.

The contact plate preferably takes the form of an extension upon a cylinder adapted to carry the lamp bulb and its reflector, which fits within the end of the external battery-containing casing.

In the form shown in Fig. 1 the cylinder in question is shown at 15, and is provided with a downward extension or projection 16, which takes the form of a complete cylindrical skirt. This skirt is adapted to fit snugly over the upper end of the battery, thus assisting in centering the same within the casing. The skirt 16 is preferably slit at intervals as indicated in dotted lines at 17, in order to give it resilience and to accommodate slight differences in the sizes of the batteries.

The upper end of the ring 15 is nearly closed by a top 18, having a depending central threaded sleeve 19, into which screws the lamp bulb stem 20, with or without a reflector 23.

To prevent short-circuit, the ring 15 is provided with an insulating covering 21, which fits snugly within the top of the casing, and, in order the better to place the whole, insulation 22 is provided, which fits over the ring 15 and extends outward sufficiently to rest upon the end of the casing 12. This insulation preferably takes the form of a separate washer secured and under the reflector 23.

The reflector 23 is also held in place in any convenient manner, as by the threaded neck passing through the insulation 22. This reflector does not touch any external metal part.

The parts described are all held in place preferably by the usual lens 24 and lens holder 25; the latter screwing onto the upper end of the casing 12.

Where the casing which carries the battery is made of fiber or other insulating material, the insulation 21, 22, may be dispensed with. This is shown in Fig. 2, wherein the casing 12 is supposed to be made of fiber, and where the ring 15 is supported by a flange 26 resting on the end of the casing,

and out of contact with the external metal parts.

In either case it is clear that it is not essential (although more convenient) to have the extension 16 form a complete skirt or cylinder. As shown in Fig. 6, this extension may be limited laterally; for instance in the form of a finger 27. It is only necessary to make sure that this comes under the end of 10 the contact-making spring.

This last named spring is shown at 28 fixed at its lower end under a covering plate 29, and having a contact-making tip (preferably recurved) as shown at 30. This tip 15 can be pressed down through the opening 31 in the casing 12 by means of a separable push button 32, held and guided by the cover plate 29 until said tip touches the interior contact plate extension 16 (or 27).

20 This contact closes the circuit through the lamp and through the metallic casing 12 and cover casing 29, in the form shown in Fig. 1.

In the form shown in Fig. 2 the lamp is also lighted by this contact, but, in this instance, the current passes from the cap 13 25 to the cover casing 29 by means of the metal screw ring 33, and the internal conducting strip 34.

Where prolonged contact is desired, the 30 spring 28 can be held down against the interior contact plate by means of a supplemental button 35, which may be made to slide forward on the cover plate 29. This button has an inwardly projecting portion 36 35 which carries a cam plate whose curved portion 37 rests normally within the curve 38 on the spring 28. When this cam is pushed forward by means of the sliding button 35, it presses against the part of the 40 spring 28 in front of the curve 38, thereby depressing the spring and causing operative contact as above described. Upon drawing back the button 35, the normal position shown in Fig. 4 is restored, and the contact 45 is broken.

Various changes can be made in the apparatus above described without departing from the scope of the invention, and the claims are not intended to be limited to the details herein shown and described. 50

What I claim is—

1. A portable electric light comprising an external battery-containing casing, a lamp bulb carried thereby, a removable contact plate adapted to be slipped into position between the casing and battery, said contact plate being connected electrically with the outer terminal of the lamp bulb and being normally insulated from all exterior metal parts of the device, and means on said casing adapted to close circuit through the battery and lamp by contact with said removable contact plate. 55

2. The apparatus set forth generally in claim 1 hereof, wherein the removable contact plate takes the form of an extension on a cylinder fitting into the end of the external casing. 60

3. The apparatus set forth generally in claim 1 hereof wherein the removable contact plate takes the form of a cylindrical skirt adapted to fit over the upper end of the battery when inserted. 70

4. The apparatus set forth generally in claim 1 hereof wherein the removable contact plate forms an extended portion of a ring surrounded by insulating material adapted to fit into the external casing. 75

5. Apparatus of the character set forth generally in claim 1 wherein the contact plate 80 takes the form of a metal cylinder adapted to fit the casing and having an extended portion overlapping the battery to form a contact member, said cylinder being partly closed at one end by a wall provided with a 85 central threaded portion.

In testimony whereof I have hereto set my hand on this 2nd day of March, 1920.

HARRY M. KORETZKY.
